JOHN L. McMILLAN, OF SYRACUSE, NEW YORK, ASSIGNOR TO McMILLAN BOOK COMPANY, OF SYRACUSE, NEW YORK, A CORPORATION OF NEW YORK

VISIBLE INDEX BINDER

Application filed June 11, 1928. Serial No. 284,448.

This invention relates to a new and improved loose leaf binder of a type adapted to be used as a visible index binder.

When it is desired to use a loose leaf binder as a visible index binder it is customary to have the sheets which are used with the binder of such a height in relation to the height of the binder itself that they may be placed in the binder in overlapping relation so that a portion of each sheet is at all times exposed, the indexing indicia being placed on the exposed portion of a sheet. In using books of this character it is frequently necessary to remove a sheet from the binder and place a new one in the binder in lieu thereof. The position in the binder of the sheet which is removed will necessarily vary but it is customary to place the replacing sheet at the bottom of the binder. This requires that the sheets which were below the sheet removed be moved upwardly in the binder in order to leave a space at the bottom for the reception of the replacing sheet.

In order to accomplish the movement of sheets in the binder easily and accurately it is desirable to provide a means whereby the position of the sheets with reference to the prongs on which they are carried may be changed while the sheets are at all times retained on prongs. In order that this transfer may be accomplished it is necessary to open the book so that the ends of the prongs may be released to permit the movement of the sheets in relation thereto. In order to facilitate the transferring operation it is desirable that the book be locked in the proper open position while the transfer is being accomplished, and the main object of my invention is to provide a locking means which will not only lock the book in the closed position but will also lock the book in the proper open position when the sheets are being transferred.

Other objects and advantages relate to the size, shape and arrangement of parts all as

will more fully appear from the following description taken in connection with the accompanying drawings in which:

Figure 1 is a top view of the prong assembly of my book in the closed position. 50

Figure 2 is a top view of the prong assembly of my book with the prongs in the proper open position for transfer of the sheets and with the prong-carrying plates in the transferring position. 55

Figure 3 is a top view of the prong assembly with the book in the open position to permit the removal of sheets.

Figure 4 is a section on line 4-4 of Figure 5. 60

Figure 5 is a section on line 5-5 of Figure 1.

Figure 6 is a section on line 6-6 of Figure 2.

Figure 7 is a section on line 7-7 of Figure 3. 65

It will be understood that my locking device may be used with different types of loose leaf binders and also with binders which have different types of transferring means, but for the purpose of explaining the construction and operation of my device I have here shown it in conjunction with a particular type of loose leaf binder in which the transferring means is provided by the longitudinal movement of one prong-carrying plate in relation to the other prong-carrying plate. 70

The opposed prong-carrying plates are carried by two housings which are hingedly connected together and which in combination provide a back for the binder. These housings —1— and —2— are similar in construction so that a description of one will be a description of the other. 80

Housing —1— has an inner face —3— and a top face —4— in right-angular relation thereto and carries a vertically extending back —5— extending upwardly from the outer edge of upper face —4—. A back plate —6— has its bottom face —7— disposed in a plane approximately parallel with the plane 85

of which upper face —4— is disposed and with back plate —8— extending vertically from the rear longitudinal edge of bottom face —7—. Back plate —8— extends vertically to a short distance beyond the top edge of back —5—. A prong-carrying plate —9— having a plurality, in this case shown as ten, of arcuate rods or prongs —10— affixed thereto by riveting or other convenient means is positioned adjacent the inner face of back —5— and prong-carrying plate —9—, back —5— and back plate —8— are then rigidly secured together by rivets —11— or other convenient means. The upper edge of back plate —8— is formed in such a way that it may be joined to a cover —12— by means of a hinge connection to permit the movement of cover —12— in relation to housing —1—. The bottom edge of inner face —3—, as perhaps may best be seen from Figures 2 and 3, is provided with a plurality of eyes —13— and the opposing inner face —3— of housing —2— is also provided with a plurality of eyes —14—, the distance between the eyes —13— being greater than the width of eyes —14— and the distance between eyes —14— being greater than the width of eyes —13— so that when housings —1— and —2— are joined together in hinged relation by the insertion through eyes —13— and —14— of a pintle —15—, housings —1— and —2— may be moved longitudinally in relation to each other by the movement of eyes —14— on pintle —15—, pintle —15— being fixed in eyes —13— carried by housing —2—. The extent of such longitudinal movement of housing —2— in relation to housing —1— is in this case shown as the distance between the centers of two adjacent holes in the sheets, not shown, used with the binder, but it will be obvious that the extent of such longitudinal movement may be varied as desired.

As perhaps may best be seen from Figure 4 my locking means consists of a rod —16— affixed in the opposite ends of housing —2—, such ends being formed from downwardly bent portions of top face —4— of housing —2—. A pair of similar latches —17— and —18— of arcuate metal strips and having a plurality, in this case shown as three, of notches —19— on one edge are pivotally and slidably mounted on rod —16— in spaced relation. Latches —17— and —18— extend through slots —20— and —21— in the inner face —3— of housing —2—, such slots being wider than the width of latches —17— and —18—. Latches —17— and —18— also extend through slots —22— and —23— in housing —1—. I provide in housing —1— on the inner side of inner face —3— a keeper rod —24— slidably mounted on pins —25— and having slots —26— and —27— to which latches —17— and —18— extend. The width of slots —26— and —27— is such that when keeper rod —24— is pushed inwardly

latches —17— and —18— may move freely through slots —26— and —27— but when keeper rod —24— is pulled outwardly the edges of slots —26— and —27— will engage notches —19— in latches 18 and 17, respectively, to prevent the movement of latches —17— and —18— in relation to keeper rod —24—. In order that keeper rod —24— may be normally releasably held in the outward position with the edges of slots —26— and —27— in engagement with notches —19— I provide a spiral spring —28— having one end affixed to housing —1— and having the other end affixed to keeper rod —24—.

The spacing of notches —19— in latches —17— and —18— is such that they will engage keeper rod —24— in three different relative positions of housings —1— and —2—. In the first position the book is closed as shown in Figures 1 and 5, in the second position the book is in the proper open position for the transfer of sheets as shown in Figures 2 and 6 and in the third position the book is open to permit the removal of sheets as shown in Figures 3 and 7.

When it is desired to transfer a sheet in the binder, the sheets are moved over in position on to the prongs carried by housing —2—, one of such sheets —29—, partially broken away, being shown in position in Figure 2. The keeper rod —24— is then pushed inwardly to release latches —17— and —18— and the binder is opened to the position shown in Figure 2. Housing —2— is then moved longitudinally in relation to housing —1— into the position shown in Figure 2. The sheet —29— which it is desired to transfer is moved upwardly on the prongs —10— on housing —2— and from such prongs —10— on to the prongs —10— on housing —1—. The housing —2— is then moved longitudinally of housing —1— to the normal position, latches —17— and —18— are released from keeper rod —24—, and the book is closed into the position shown in Figure 1.

As perhaps may best be seen from Figure 2, the transfer of a sheet —29— from the prongs —10— on housing —2— to the prongs —10— on housing —1— while the housing —2— is in an offset relation with housing —1— causes each prong on housing —1— to enter an aperture —30— in a sheet —29— next adjacent to the aperture —30— which it would enter if the book were closed with housings —1— and —2— in the normal position with relation to each other. This being the case when the housing —2— is moved back to the normal position with relation to housing —1— and the book is closed, the sheet —29— will have moved upwardly in the book the distance between two apertures —30—.

In order that both ends of prongs —10— may be held rigidly in position when the

book is closed I provide in each of the prong-carrying plates —9— orifices —31— which the ends of the prongs —10— carried by opposing prong-carrying plate —9— enter when the book is closed.

It will be understood that the number of prongs —10— carried by the prong-carrying plates —9— may be varied as desired and it will also be understood that the extent 10 of the relative longitudinal movement of housing —2— in relation to housing —1— may be varied so that a sheet will be transferred a distance greater than the distance between two adjacent apertures —30—. It 15 will also be understood that if desired my latches —17— and —18— may be varied in length as may also be the number of notches in latches —17— and —18— so that the book may be locked in more than the three positions indicated.

It will also be understood that my arrangement of a locking latch and keeper bar is adapted to be used with any type of binder in which the prongs are adapted to be moved 25 to and from each other, for although I have shown and described a specific structure and form of part as an exemplification of an embodiment of my invention I do not desire to restrict myself to the exact shape, form 30 or relation of parts as various changes may be made within the scope of the appended claims.

What I claim is:

1. In a device of the class described, opposed back members hingedly connected together, a plurality of prongs secured to each of said back members, said back members being relatively movable on the axis of the hinge, a latch having one end slidably mounted in one of the back members and having its other end extending into the other back member, a keeper slidably mounted in the last-named back member, and means for releasably positioning the keeper in the latch.

45 2. In a device of the class described, opposed back members hingedly connected together, a plurality of prongs secured to each of said back members, said back members being relatively longitudinally movable on 50 the axis of the hinge, a latch having one end mounted in one of the back members and having its other end extending into the other back member, means permitting longitudinal movement of the back member in relation to the latch mounted therein, a keeper slidably mounted in the other back member, and means for releasably positioning the keeper in the latch.

60 3. In a device of the class described, opposed back members hingedly connected together, a plurality of prongs secured to each of said back members, said back members being relatively longitudinally movable on the axis of the hinge, an aperture in one of 65 the back members, a latch means for mount-

ing said latch in said back member to extend outwardly through the aperture and to permit longitudinal movement of the latch relative to the back member, the aperture being relatively longer than the width of the latch 70 to permit said longitudinal movement, an aperture in the other back member for the reception of the latch, a keeper slidably mounted in the last-named back member, and means for releasably positioning the keeper in the latch.

4. In a device of the class described, opposed back members, a plurality of eyes in spaced relation on one longitudinal edge of each back member, a pintle extending through said eyes, the width of the eyes on a back member being less than the distance between the eyes on the other back member to permit longitudinal movement of the back members on the pintle, a plurality of prongs secured to each of the back members, a latch having one end slidably mounted in one of the back members and having its other end extending into the other back member, a keeper slidably mounted on the last-named back member, and means for releasably positioning the keeper in the latch.

5. In a shift binder of the character described having a pair of back members hinged together, and having provisions whereby one back member may shift relative to the other thereof, the combination therewith of means for holding the back members releasably in a selected one of a plurality of relative hinged positions in all shifted positions of one back member relative to the other thereof, and means under control of the operator for releasing said holding means.

6. In a shift binder of the character described having a pair of back members hinged together, and having provisions whereby one back member may shift relatively to the other thereof on the hinged connection between them, the combination therewith of releasable holding means for maintaining the back members in a selected one of a plurality of relative hinged positions during shifting movements of one back member relative to the other thereof on their hinged connection, and means under control of the operator for releasing said holding means whereby the back members may open fully, the arrangement being such that when the back members are moved towards each other from the fully open position into a partly open position, said holding means will automatically again hold the back member in that partly open position.

7. In a shift binder of the character described having a pair of back members hinged together with provisions whereby one back member may shift on the hinge connection relative to the other thereof, the combination therewith of releasable locking means for holding the back members in closed position,

or for holding the back members in a selected one of a plurality of open hinged positions, said locking means including a holding element elongated in the direction of the hinge connection between the backs and providing a sliding connection whereby one back member may be shifted relative to the other thereof while the back members are maintained in such selected position.

30 In witness whereof I have hereunto set my hand this 1st day of June, 1928.

JOHN L. McMILLAN.
